UNITED STATES PATENT OFFICE.

SIGMUND HERMANN, OF NEW YORK, N. Y., ASSIGNOR TO ETTIE HERMANN.

HANDLE FOR SATCHELS AND THE LIKE.

1,180,716.

Specification of Letters Patent. Patented Apr. 25, 1916.

Application filed October 9, 1915. Serial No. 55,124.

To all whom it may concern:

Be it known that I, SIGMUND HERMANN, a resident of the city of New York, in the county of New York and State of New York, have invented a certain new and useful Improvement in Handles for Satchels and the like, of which the following is a specification.

My invention relates to handles to be used on satchels, valises and the like, and has for its primary object to provide a construction characterized by superior simplicity, and efficiency, and having a capacity for sustaining greater weights, and improving the wearing qualities by virtue of this new construction.

A further object of my invention is to provide a handle which will keep its shape indefinitely by providing it with a filler block made of such material as will not change its shape due to the amount of weight carried, or by reason of becoming moist, either through the perspiration of the hand, or by being carried during rainy weather.

Still another object of my invention is to provide a handle for the articles described, which has no seams which are sewed, or which extend beyond the rounded surface, in such a way as to cause callous on the hands, by being used extensively during a day's travel.

Still another object of my invention is to provide a handle in which none of the strains are taken directly upon the leather coating of the handle, therefore, avoiding the shabby look which is usual in handles where the strain is taken by the leather itself, as well as by some restraining object on the inside.

A preferred embodiment of my invention is illustrated on the accompanying drawings, wherein the same character of references are employed to indicate the same parts throughout the several views.

On the said drawings, Figure 1 is a perspective view of the handle complete. Fig. 2 is a longitudinal section, taken through 4-4 of Fig. 4, showing the various parts in their respective places. Fig. 3 is a plan view of the filler-block showing the position of the tie-wire holes in the slot of the said filler-block. Fig. 4 is a transverse section taken through 2-2 of Fig. 2. Fig. 5 is a detailed view, showing the construction of the loop at the end of the weight carrying wire. Fig. 6 is a detailed view of the flexi-

ble material used in covering the loop end shown in Fig. 5.

Referring more particularly to the drawings, I utilize the filler-block 1, which is so shaped as to conform most conveniently to the grip of the hand, and, at the same time be properly arched to take the strain put upon it by virtue of carrying such loads as may be put in the satchel or the like. In 65 this filler-block we have a slot 2, in which the wire 3, after being covered by a flexible strap 4, made of flexible material, preferably leather, is placed and rigidly fastened by means of tie-wires 5, which are 70 drawn back and forth through the small holes 6, which are drilled through the filler-block 1, as shown in Fig. 3. These wires 5, at the lower end of the filler-block 1, are covered with a suitably shaped piece of 75 flexible cover plate 7, which is fastened by means of an adhesive, or may at the proper points be tacked into place, but in actual practice, an adhesive would be preferable. The cover plate 7, being placed in this position to obviate the roughness on the lower side of the handle caused by the wires coming through the filler-block. The ends of the carrying wire 3 are coiled up in a loop. This loop is covered with an ornamentally 85 shaped thimble 9, which is made of some shape-retaining material, preferably a metal around which the flat portion 10, of the strap 4, is placed and also held into position by some adhesive.

The wire 3, with its loops being thus covered is set into slot 2, and pressed down tightly, and then sewed in with the tie-wires 5. After this is done the entire handle is covered with a thin veneer of leather 11, 95 and 11^a. 11^a, being placed around the loops first for the convenience of manufacturing, and that, entirely covered by this thin material preferably leather 11. The veneer 11 is carried around from the lower part of 100 the handle, to the upper part, and its ends turned in to the slot 2. After the covering is turned in I place a wedge-piece 12, which is first covered on three sides, bottom, and two sides, with an adhesive and press it into 105 place so as to form a smooth surface at the top of the handle. This wedge-piece, keeps the ends of the veneer covering in the slot, and prevents the fraying on the ends due to wear. After this is done, and the handle 110 is complete I place rings 13, through the loops 8, on either side of the handle.

Having thus described my invention, what I claim as new, and desire to secure and protect by Letters Patent of the United States is;—

5 In a handle of the class described, the combination of a slotted shaping-block, a tension member having loops at each end, said loops reinforced with thimbles, transversely corrugated to fit the wire loops; a
10 wire binding said tension member into the slot of the filler-block, a cover plate of soft material, to form an even surface over the loops of the tie wires, an outer coating of

veneer of thin leather, a wedge for holding the edges of said outer coating into the slot 15 of the filler-block and to smooth off the upper surface of the filler-block, and rings for connecting said loops in the tension member to a satchel or bag.

In testimony whereof I affix my signature in the presence of two witnesses.

SIGMUND HERMANN.
